(57) **CLAIM**

The ornamental design for a kitchen hood, as shown and described.

DESCRIPTION

FIG. 1 is a perspective view of a kitchen hood constructed in accordance with an embodiment of the present invention; FIG. 2 is a left side view of the kitchen hood shown in FIG. 1;

FIG. 3 is a front plan view of the kitchen hood shown in FIGS. 1 and 2;

FIG. 4 is a bottom view of the kitchen hood shown in FIGS. 1-3;

FIG. 5 is a bottom view of the kitchen hood shown in FIGS. 1-4;

FIG. 6 is a right side view of the kitchen hood shown in FIGS. 1-5; and,

FIG. 7 is a perspective view with the lower assembly open of an alternative embodiment of the kitchen hood shown in FIGS. 1-6.

The broken line showing of the top sides, top front, lights, switches, and bottom front of a kitchen hood is included for the purpose of illustrating environmental structure and forms no part of the claimed design.
